mesne assignments, to E. I. du Pont de Ne-
mours & Company, Wilmington, Del., a cor-
poration of Delaware

Application July 15, 1936, Serial No. 63,859

Term of patent 7 years

To all whom it may concern:

Be it known that I, Edmund H. Tyson, a citizen
of the United States, and a resident of Caldwell,
in the county of Essex and State of New Jersey,
have invented a certain new, original, and orna-
mental Design for a Plastic Tube or Similar Ar-
ticle, of which the following is a specification,
reference being had to the accompanying drawing
forming part thereof.

In the accompanying drawing:

The figure is a plan view of a plastic tube or
similar article showing my new design.

I claim:—

The ornamental design for a plastic tube or
similar article, substantially as shown.

EDMUND H. TYSON.
